UNITED STATES PATENT OFFICE

SAMUEL H. NORTON, OF MEADVILLE, PENNSYLVANIA, ASSIGNOR TO HOOKLESS FASTENER COMPANY, A CORPORATION OF PENNSYLVANIA

SEPARABLE FASTENER

Application filed October 26, 1929. Serial No. 402,702.

This invention relates to separable fasteners of the type embodying a slider which progressively interlocks or releases the fastener elements, and particularly to separable bottom stops therefor.

One of the objects of the present invention is to provide a slide fastener having a new and improved bottom stop.

Another object is to provide a slide fastener having a novel separable bottom stop, the parts of which are moved into and out of interlocking engagement by the action of the slider which interlocks and releases the fastener elements.

A still further object is to provide an improved separable bottom stop for slide fasteners, the separable portions of which may be secured directly to the material on which the fastener sections are mounted.

Still another object of my invention is to provide improved means for retaining the slider in position on one stringer while the other stringer is completely separated therefrom.

A more specific object is to provide means for retaining the slider in position at the end of one stringer which is actuated by the resilient properties of the corded edge tape of the fastener stringer.

With the above and other objects in view, the present invention may be said to comprise the separable bottom stop as illustrated in the accompanying drawings hereinafter described, and particularly set forth in the appended claims, together with such variations and modifications thereof as will be apparent to one skilled in the art to which the invention appertains.

In the drawings which illustrate a suitable embodiment of the present invention,

Figure 1 is a plan view of a slide fastener having a slider and a separable bottom stop, the fastener being partially closed;

Fig. 2 is a view similar to Fig. 1 showing the slider at the end of its opening movement and showing the parts of the bottom stop pivoted out of interlocking engagement;

Fig. 3 is a view similar to Fig. 2 showing one of the bottom stop members removed from the fastener slider;

Fig. 4 is a perspective view of the bottom stop, showing the parts thereof in interlocked position;

Fig. 5 is a perspective view of one of the bottom stop members;

Fig. 6 is a perspective view of the other bottom stop members;

Fig. 7 is a perspective view showing one method of securing the bottom stop members to a fastener tape;

Fig. 8 is a perspective view of the bottom stop member shown in Fig. 7 in reverse position, showing the fabric material to which the fastener tapes are secured being positioned on the tape;

Fig. 9 is a perspective view similar to Fig. 8 showing the fabric material positioned at opposite sides of the bottom stop member and secured thereto by a rivet; and

Fig. 10 is a perspective view similar to Fig. 9 showing the fabric material secured to the bottom stop member by stitching.

Referring to the drawings in which like numerals refer to like parts throughout the several views, separable fasteners of the type employed for continuously securing flexible flaps together along their adjoining edge portions are shown in Figs. 1 to 3. Fastener elements 1 are attached at closely spaced points to the adjoining edges of the flats or fastener tapes 2, and are so formed for interlocking engagement, the fastener tapes 2 being secured to the adjacent edges of the article to be closed or fastened by the fastener. These fastener elements 1 are progressively guided into and out of interlocking engagement by means of a slider A which is mounted for sliding movement on the fastener elements 1.

The slider A embodies a pair of spaced wing portions 4 overlying the outer sides of the fastener elements. The wing portions 4 are united at one end by an integral web 5 having angular cam surfaces 6 formed thereon. The cam surfaces intersect along the longitudinal axis of the slider A and serve to separate the fastener elements 1 when an opening movement is imparted to the slider. The wings 4 of the slider A are formed with opposed divergent guide flanges 7 at their 100

sides which serve to guide the fastener elements 1 into interlocking engagement with each other, the ends of the flanges 7 adjacent to the web 5 being spaced from the cam faces 6 to provide suitable passageways for the reception of the fastener elements 1. The slider A is, in effect, provided with an open ended passageway which branches off into divergent open ended passageways adjacent to the web 5.

An opening 8 is formed in the wings 4 adjacent the raised portions forming the cam surfaces 6 through which a cord or suitable strip of fabric is passed and tied to provide the pull member 9 for actuating the slider A.

The separable bottom stop B, as shown in Figs. 4 to 6, comprises two members 10 and 11 adapted to be interlocked with each other, each of which is secured to a fastener tape 2 adjacent to the endmost fastener element 1 mounted thereon.

The bottom stop members 10 and 11 are both of single piece construction and each is provided with a pair of spaced tongues 12 and 13.

The bottom stop members 10 and 11, as shown in Fig. 4, are preferably formed to the approximate thickness of the fastener elements and are provided with longitudinal shoulders 14 so that the slider A can be moved over the same and so that the bottom stop portion 11 can be removed through the slider passageway.

The flat longitudinal edge face 15 of the bottom stop member 11 is preferably provided with a projection or lug 16 positioned between its ends, and one of its ends is extended and reduced in width and thickness to provide a tongue 17 which forms a continuation of the flat face 15, as shown in Fig. 6. The lug 16 is tapered to provide inclined guide surfaces on its upper and lower faces. It will be noted that the end of tongue 17 is turned outward in a lateral direction from the center line of the fastener.

The flat longitudinal edge face 18 of the bottom stop member 10 is formed with a depression 19 for receiving the lug 16 of the member 11 when the members are interlocked, and is further formed with a flat narrow projection 20 at one end, perpendicular to the face 18, and has an aperture 21 to receive the tongue 17 of the member 11. The projection 20 preferably is of greater thickness than the body portion of the stop member 10, and projects beyond the top and bottom faces thereof to provide an effective stop for holding the slider A in position when the fastener elements 1 are completely disengaged, and the bottom stop members 10 and 11 are separated, as shown in Figs. 2 and 3.

One embodiment of an important feature of the invention will now be described. Notches 30 are cut in the slider to receive the stop lug 20. With the illustrated form of

stop lug 20, notches in both slider wings are required but with other forms of stops a notch in only one wing will be necessary. The side of this notch away from the stop member 10 has an inclined surface 31 forming a hook-like retaining device and an inclined guiding surface 32 leading to surface 31.

The tongues 12 and 13 extend well onto both sides of the fastener tape 2 and are secured thereto by piercing the same, forcing the metal defining the pierced opening 22 of the tongue 12 through the tape 2 and through the pierced opening in the tongue 13, and clinching the extended metal 23 of the tongue 12 over the edges of the tongue 13 defining the opening thereof, substantially as shown in Figs. 4 and 7. It is to be noted that by thus extending a portion of the metal of one tongue through the other tongue and clinching the same thereover, a rivet effect is provided which very securely and effectively holds the bottom stop members 10 and 11 in position on the ends of the tapes 2 adjacent the fastener elements 1.

As shown in Figs. 1, 8 and 9, the fastener tapes 2 are mounted between the pieces of material 24 which are a part of the article which is to be opened and closed by the fastener described. In Fig. 9, the material 24 is doubled back upon itself and is positioned at each side of the tape 2 to conceal the tongues 12 and 13 of the bottom stop member. A rivet 25 extends through the material 24 and opening 22 in the bottom stop member and is clinched over the fabric 24 to securely hold the bottom stop member and material together, thereby providing a very satisfactory securing means. The tape 2 and material 24 may be stitched or otherwise fastened together along the edges of the fastener elements 1.

Fig. 10 illustrates a modified means for securing the bottom stop member to the piece of material 26. In this construction, the tape 2 is secured to the material 26 and the threads 27 are passed through the opening 22 in the bottom stop member. If desired, a second piece of material may be positioned over the tongue 12 to conceal the same, and secured thereto in the same way as the piece 26.

It is evident that by securing the bottom stop members to the tapes and the material, in either of the manners just described, the tapes cannot be easily torn from the material, and the tongues 12 and 13 of the bottom stop members are substantially concealed.

The separable bottom stop B remains closed while the fastener elements 1 are interlocked, because of the tongue 17 of the member which extends through the aperture 21 of the member 10 and prevents relative transverse movement of the members, and the lug 16 which seats in the depression 19 and prevents relative longitudinal shifting of the members 10 and 11.

In operation, the slider A after it releases the endmost fastened elements 1, causes the bottom stop members 10 and 11 to separate and sweep through substantial arcs of movement by reason of the pivoted or hinge action, which is permitted by the engagement of the curved tongue 17 of the member 11 with the projection 20 of the member 10. This position is illustrated in Fig. 2 and as shown therein, the projecting portions of the projections 20 of the member 10 have snapped into the notches 30 formed in the ends of the slider wings 4 at the open end thereof. The projection 20 provides a suitable stop for preventing the slider A from sliding off the stop member 10. In this hinged position, the lug 16 of the member 11 clears the depression 19 of the member 10, and the member 11 can be completely separated from the member 10, by sliding it through the slider passage-way as shown in Fig. 3. The engagement of the projection 20 with the hooklike surface 31 on each of the notches 30 serves to retain the slider in position as illustrated in Fig. 3 to allow easy reinsertion of the stop member 11. The projection 20 and hooklike surface 31 are yieldingly held in engagement by the resilient action of the curved end of the corded edge tape 2. This action causes the interlocking elements to press against the slider at 33 and twist the slider clockwise thereby holding the surface 31 in contact with the projection 20.

To refasten the edges of material by interlocking the fastener elements, it is simply necessary to again insert the bottom stop portion 11 into the slider A, preferably with the left hand until the tongue extends through the aperture 21 of the member 10. The slider which is preferably being held with the right hand, is then moved along the fastener elements 1 by pulling on the pull member 9 to rock or pivot the bottom stop members until the lug 16 of the member 11 seats in the depression of the member 10 to interlock the same, at the same time bringing the lowermost fastener elements into interlocked position, as shown in Fig. 1.

It is readily apparent that the present invention provides a very simple and efficient stop member which is separated, to completely separate the edges of the material to which the fastener elements are secured, merely by the opening movement of the slider member.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

What I claim as my invention is:

1. A separable end connection for a sepa-

rable fastener having interlocking fastener elements mounted on flexible tapes and a slider slidably mounted thereon for moving said elements into and out of interlocking engagement, comprising a pair of stop members, one of said members having a depression in its side face and an apertured projection, and the other of said stop members having a tongue adapted to extend longitudinally through the aperture in said projection and a lug adapted to extend into said depression in said first mentioned member, said depression being so formed that when cooperating with the lug, the end connecting members are prevented from moving transversely with respect to each other.

2. A separable end connection for a separable fastener having interlocking fastener elements mounted on flexible tapes and a slider slidably mounted thereon for moving said elements into and out of interlocking engagement, comprising a pair of interlocking stop members adapted to be spread apart by said slider, one of said members having a depression in its side face and a recessed projection extending transversely from said side face, and the other of said members having a longitudinal tongue adapted to extend longitudinally through the recess in said projection and a lug on its side face adapted to extend into said depression in said first mentioned stop member, said depression being so formed that when cooperating with the lug, the end connecting members are prevented from moving transversely with respect to each other.

3. A separable end connection for a separable fastener having interlocking fastener elements mounted on flexible tapes and a slider slidably mounted thereon for moving said elements into and out of interlocking engagement, comprising a pair of interlocking stop members adapted to be spread apart by said slider, one of said members having a depression in its side face and a recessed projection extending transversely from said side face, and the other of said members having a longitudinal tongue adapted to extend through the recess in said projection and a lug on its side face adapted to extend into said depression in said first mentioned stop member, said lug having inclined guide surfaces on its upper and lower faces, said slider when moved to disengage said fastener elements and separate said stop members being adapted to engage the projection of said first mentioned stop member while the other of said stop members is drawn through said slider, said depression being so formed that when cooperating with the lug, the end connecting members are prevented from moving transversely with respect to each other.

4. In a separable fastener a pair of fastener stringers having rows of fastener elements attached to adjacent longitudinal

- edges of said stringers, a slider movable along said stringers to engage and disengage said elements, said slider having diverging channels causing flexing of said stringers outwardly from each other at the position of the slider, a pair of separable end connecting members on said stringers, a stop on one of said members to retain the slider thereon, the other end connecting member being insertable and removable through the slider while adjacent said stop into and out of engagement with its cooperating member, and cooperating means on said member having the stop and said slider operable by a relative twisting movement of the slider to retain the slider in position adjacent said stop while the opposing connecting member is disconnected, said slider being held against said retaining means by the resilient action of the stringer on which it is located.
5. In a separable fastener, a pair of fastener stringers having rows of cooperating fastener elements along adjacent longitudinal edges, a slider having diverging channels movable along said stringers to engage and disengage said elements, said slider flexing said stringers outwardly of each other as it passes along said stringers, and a separable end connection comprising end connecting members adjacent the ends of said rows of elements, a stop on one of said members to prevent the slider being removed therefrom, a notch in one of the wings of said slider adapted to receive a portion of said stop, said notch being held in interlocking relation with said stop by the resilient action of the stringer tending to twist said slider relative to the end connecting member thereby to retain said slider in position for easy removal and insertion of the opposite end connecting member.
6. A separable end connection for a separable fastener having interlocking fastener elements mounted on flexible tapes and a slider movable along the said elements to engage and disengage the same, said connection comprising a pair of end connecting members adapted to be disconnected to permit complete separation of the opposite sides of said fastener, one of said members having a recess in its longitudinal face opening laterally but closed both longitudinally and transversely, a projection on the longitudinal face of said other member adapted to enter said recess laterally and to be held by the walls of said recess against relative transverse and longitudinal sliding movement in all directions, and separate interlocking means on said members for holding the same against lateral separation when interlocked.
7. A separable end connection for a separable fastener having interlocking elements mounted on flexible tapes and a slider mounted for sliding movement along said elements to engage or release the same, comprising a pair of end connecting members, said members having a cooperating depression and lug in their side faces to prevent relative transverse movement when the members are connected, one of said members having a laterally projecting portion with an opening therethrough, and the other of said members having a tongue extending longitudinally with its end curved outwardly for insertion through said opening to hold the members against lateral separation.
8. In a separable fastener, a pair of flexible fastener stringers comprising tapes having rows of spaced fastener elements attached to their adjacent longitudinal edges, a slider movable along said stringers to engage and disengage said elements, said slider having a Y-shaped channel through which said stringers pass during movement of the slider and which causes flexing of said tapes in the locality of the slider, a pair of separable connecting members arranged on the ends of said stringers, a projection on one of said members constituting a stop for the slider, a portion of the flexible stringer being housed within the slider channel when said slider is against the stop whereby a twisting force is applied to the slider, a notch in said slider having a hook-like portion adapted to engage over an edge of said projection and to be held against the same by said twisting force to retain the slider against accidental displacement on the end of one stringer while the other stringer is separated therefrom.
- In testimony whereof I affix my signature.
- SAMUEL H. NORTON.
